UNITED STATES PATENT OFFICE.

JOHN FLINDALL, OF CHICAGO, ILLINOIS.

TIME-LOCK.

No. 884,807.

Specification of Letters Patent.

Patented April 14, 1908.

Application filed November 30, 1906. Serial No. 345,765.

To all whom it may concern:

Be it known that I, JOHN FLINDALL, a citizen of the United States, residing at Chicago, in the county of Cook and State of Illinois, have invented certain new and useful Improvements in Time-Locks; and I do hereby declare the following to be a full, clear, and exact description of the invention, such as will enable others skilled in the art to which it appertains to make and use the same.

The present invention relates to improvements in time locks, and has for its primary object to provide a simple and efficient mechanism for preventing the locking bolt from being retracted by the use of a key, except at a predetermined time.

To this end the invention consists essentially of a movably mounted wall or barrier interposed between the key and the locking bar, and of means for removing the wall or barrier at the desired time.

A further feature of the invention resides in the provision of a pivoted arm for controlling the movements of the barrier, and of means whereby said arm is operated through the means of a clock.

With these and other objects in view, the invention comprises certain other novel constructions, combinations and arrangements of parts, as will be hereinafter fully described and claimed.

In the drawings:—Figure 1 is a vertical, longitudinal, sectional view through a toy safe provided with a lock constructed in accordance with the invention. Fig. 2 is a vertical, transverse, sectional view through the same.

Referring to the drawings, the numeral 1 designates the casing or walls of a safe, and 2 a door for the safe. This door 2 is provided with a locking bar 3 which is slidably mounted thereon in the usual manner, and is normally caused to move forwardly so as to assume a locked position by means of the spring 4 which bears against a pin 5 projecting from the locking bar, and is connected to the door 2. When in a locked position as shown in Fig. 1, one end of the locking bar engages a socket 30 formed in the body portion of the safe. The lower portion of the locking bar 3 has a notch 6 formed therein, and a key-hole 7 is located in the door 2 immediately below the locking bar 3 so that a key 8 inserted through the said key-hole can

be turned so as to retract the locking bar and thereby unlock the safe.

In order to prevent the key 8 from entering the notch 6, except at a predetermined time, a wall or barrier 9 is normally interposed between the key and the locking bar, and this barrier 9 is shown in the drawings as being in the nature of an annular flange carried by a wheel 10. This annular flange, however, is formed with a cut-away portion 11, and when the wheel 10 is turned so that the cut-away portion is located between the key and the locking bar, the former can be turned so that the web thereof will enter the notch 6 and withdraw the said locking bar into an unlocked position.

The wheel 10 carrying the annular flange 9 is pivotally mounted upon a pin carried by projection 12 upon the inner side of the door 2 and is provided around its periphery with a plurality of teeth 13, one side of each of the teeth being preferably inclined, while the opposite side has a radial direction. It will also be observed that the projection 12, has formed in connection therewith a pair of arms or guide members 14, for the key 8.

For the operation of the wheel 10 a pivoted arm 15 is employed, which has its lower end pivotally connected to the door 2 at 16, while its upper end is bifurcated and formed with two oppositely disposed pieces 17, which coöperate with an eccentric member 18 to produce a vibrating movement of the arm 15. Pivotally connected to the arm 15 at an intermediate point is a pawl 19, the extremity of which is bent downwardly, as indicated at 20, and engages with the teeth 13 upon the wheel 10. With this construction it will be apparent that when the arm 15 moves in one direction, the extremity of the pawl 19 will engage with the radial side of one of the teeth 13, and cause the wheel 10 to revolve, while, when the arm 15 moves in the opposite direction, the pawl 19 will slip over the inclined sides of the teeth. As a safeguard against any rearward turning of the wheel 10, it may be found desirable to employ a locking pawl, such as indicated at 21. In the present instance, this locking pawl extends in an opposite direction to the pawl 19 and engages with the teeth 13, in such a manner as to prevent any backward movement of the wheel 10 when the pawl 19 is slipping over the inclined sides of the teeth.

The eccentric member 18 receives motion from a clock 22, carried by the door 2, through the medium of a train of gears 23, which are so proportioned that the eccentric member completes one revolution in a fixed period of time, preferably 24 hours. With this arrangement it will be apparent that for every revolution of the eccentric member, the wheel 10 will be revolved through a distance corresponding to one of the teeth 13, and where the eccentric makes one revolution every 24 hours, the number of days which must elapse before the locking bar can be retracted, will be indicated by the number of teeth 13, which the pawl 19 must pass over in order to move the cut-away portion 11 of the annular flange 9 between the key 8 and the locking bar. For the purpose of enabling the mechanism to be set so that the key can be employed to withdraw the locking bar at the end of a fixed number of days, a pointer 24 is carried by the wheel 10 and an indicating member 25 by the walls of the clock 22. This pointer 24 is so arranged that when it is turned around so as to be opposite the indicating member 25, the cut-away portion of the annular flange 9 is in such a position as to enable the key to be employed for retracting the locking bar 3. With this construction it will be apparent that the number of teeth 13 which must pass under the indicating member 25 before the pointer 24 is brought to a position opposite the said member 25 will indicate the number of days which must elapse before the safe can be opened.

In the preferred construction of the invention shown in the drawings, the upper portion of the door 2 is formed with an opening 26, and the face of the clock 22 fits against the opening 26 so as to be readily visible therethrough. A partition 27 is also employed to protect the mechanism of the lock which is all carried by the door 2.

What I claim is:

1. In a time lock, the combination of a locking mechanism, a key therefor, a toothed wheel, a laterally projecting annular wall carried by the toothed wheel and normally interposed between the key and the locking mechanism, said wall being provided with a cut-away portion to enable the key to operate therethrough, a pivoted member carrying a pawl engaging the toothed wheel, and means for operating said member.

2. In a time lock, the combination of a locking mechanism, a key therefor, a wheel, a laterally projecting wall carried by the wheel and normally interposed between the key and the locking mechanism, said wall being provided with a cut-away portion to enable the key to operate therethrough, a pivotally mounted arm provided with means for turning the wheel, and means for operating said arm.

3. In a time lock, the combination of a locking mechanism, a key therefor, a wheel carrying an annular wall which normally prevents the use of the key, the said annular wall provided with a cut-away portion, and means for turning the wheel to enable the key to operate through the cut-away portion in the annular flange at a predetermined time.

4. In a time lock, the combination of a locking mechanism, a key therefor, a toothed wheel, an annular wall carried by the toothed wheel, and normally preventing the use of the key, the said annular wall having a cut-away portion, a pawl engaging the toothed wheel and turning the same to enable the key to operate through the cut-away portion of the annular flange at a predetermined time and a member carrying the pawl and imparting motion to the same.

5. In a time lock, the combination of a locking mechanism, a key therefor, a toothed wheel, an annular wall carried by the toothed wheel and having a cut-away portion, the said annular wall normally preventing the use of the key, a pivotally mounted arm, and a pawl carried by said arm and engaging the toothed wheel to turn the same to enable the key to operate through the above-mentioned cut-away portion of the annular flange at a predetermined time and means for imparting motion to the pivotally mounted arm for rotating said toothed wheel.

6. In a time lock, the combination of a locking mechanism, a key therefor, a toothed wheel, an annular wall carried by the toothed wheel and having a cut-away portion, the said annular wall normally preventing the use of the key, a pivoted arm, an eccentric member operating said arm, and a pawl carried by the reciprocating arm and engaging the toothed wheel whereby the key can operate through the before-mentioned cut-away portion of the annular wall at a predetermined time.

7. In a time lock, the combination of a notched locking bar, a key designed to engage the notch in the locking bar to withdraw the latter, a wheel, a flange carried by the wheel and normally interposed between the key and the notch in the locking bar, said flange being provided with a cut-away portion for accommodating said key and means for turning the wheel to permit the withdrawal of the locking bar at a predetermined time.

8. In a time lock, the combination of a locking mechanism, a key therefor, a barrier normally interposed between the key and the locking mechanism, a pivoted arm controlling the movements of the barrier, an eccentric member operating said arm, a clock mechanism, and means whereby motion is imparted from the clock mechanism to the eccentric member to remove the barrier at a predetermined time.

9. In a time lock, the combination of a locking mechanism, a key therefor, a wheel, a wall carried by the wheel and normally interposed between the key and the locking mechanism, the said wall having a cut-away portion, means for imparting motion to the wheel whereby the key can operate through the cut-away portion of the wall at a predetermined

time, and indicating means whereby the period of time can be regulated.

In testimony whereof I affix my signature ¹⁰ in presence of two witnesses.
